UNITED STATES PATENT OFFICE.

CARL C. P. MEYER, OF YANKTON, DAKOTA TERRITORY.

IMPROVEMENT IN DUMPING-CARS.

Specification forming part of Letters Patent No. **147,341**, dated February 10, 1874; application filed December 6, 1873.

To all whom it may concern:

Be it known that I, CARL C. P. MEYER, of Yankton, in the county of Yankton and Territory of Dakota, have invented a new and valuable Improvement in Gravel-Cars; and I do hereby declare that the following is a full, clear, and exact description of the construction and operation of the same, reference being had to the annexed drawings making a part of this specification, and to the letters and figures of reference marked thereon.

Figure 1 of the drawings is a representation of a side view of my gravel-car. Fig. 2 is a sectional view of the same. Fig. 3 is a plan view of the same.

This invention has relation to cars for ballasting railroads; and it consists in combining with a platform-car a hopper-shaped receptacle and a leveling device, as will be hereinafter explained.

In the annexed drawings, A represents the platform of the car, and B the receptacle for containing gravel or other material suitable for ballasting railroads. This receptacle B has four inclined sides, and is the shape of a truncated pyramid inverted, so that its smallest end extends down below the horizontal plane of the axles of the truck-wheels. The receptacle B may be made of boiler-iron, and it should be so applied to the platform A that its discharging end is in the center of the

roadway, and as near as practicable to the cross-ties of the rails. C C' are two doors, which are hinged at *a a*, and are firmly held by means of hooks and levers D D' catching under pins *c c*. The doors C C' can be opened when it is desired to discharge the load by simply moving the hand-levers D'. G represents an angular leveling-blade, which is secured to the rear wall of the receptacle by rods *j*, and which is arranged in a proper position for leveling or spreading the gravel laterally as the same is discharged from the receptacle B. In practice, two of these levelers will be used, one arranged in front and the other behind the discharge-opening of the receptacle B, so that the gravel will be leveled whichever way the car be moved.

This car will also be found very useful for carrying grain and other substances.

What I claim as new, and desire to secure by Letters Patent, is—

The angular leveler G, combined with the hopper-shaped receptacle B, as and for the purpose set forth.

In testimony that I claim the above I have hereunto subscribed my name in the presence of two witnesses.

CARL C. P. MEYER.
